DOOR LATCH

Geoffrey L. Wilks, Billingshurst, England

Application May 25, 1955, Serial No. 511,000

Claims priority, application Great Britain May 27, 1954

2 Claims. (Cl. 292—46)

Although applicable for use generally the door latching device forming the subject of the present invention has been designed primarily for use in connection with the doors of vehicles. With the use of improved draught excluding seals in connection with the doors of motor vehicles difficulty is often experienced in closing and latching such doors especially when the windows are closed and the chief object of the invention is to evolve a door latching device with which the door can be closed quietly without slamming and with a minimum of effort on the part of the operator.

A door latching device in accordance with the present invention and intended particularly for use in connection with the doors of motor vehicles includes a locking jaw for co-operating with a peg or its equivalent either said jaw or peg being associated with the door and the other component being associated with a fixed part, spring urged toggle link or equivalent mechanism movable through a dead centre position as a result of engagement of the jaw and peg or an additional protuberance during closing movement of the door and for drawing the jaw and peg together into interlocking engagement and the door into its fully closed position.

Movement of the toggle link or equivalent mechanism initially through a dead centre position to stress its associated spring may be performed either by operation of the door handle in the process of opening the door or alternatively by initial opening movement of the door itself, the former arrangement being preferably employed.

Referring to the drawings:

Figure 1 illustrates the door latching device in rear elevation;

Figure 2 is a sectional side elevation;

Figure 3 is a sectional side elevation illustrating the toggle lever mechanism and its associated parts;

Figure 4 is a plan view;

Figure 5 is an elevational view of the complete mechanism as fitted to a vehicle door and looking from the interior of the vehicle;

Figure 6 is a fragmentary sectional view illustrating one of the outside door handles and associated parts.

The door latching device illustrated has been designed for inclusion in a motor vehicle door, the device being operated in an opening sense directly by means of an outside handle and indirectly through the medium of a second handle located within the vehicle.

The device includes two main supporting plates 1 and 2 which are spaced apart and carry fixed bearing members 3 and 4 of the knife edge type with which engage components 5 and 6, component 5 being carried by a pair of spaced links 7. Component 6, the lower end of which terminates in a knife edge for co-operating with component 4, has associated with it a coiled compression spring 8, the upper part of component 6 being in the form of a rod 9, its upper extremity sliding in a bearing member 10 pivotally associated at 11 with the pair of links 7. The lower ends of links 7 are formed with two flat faces 12 and 13, the point where they intersect being engageable by a knife edge 14 on bearing member 10 to limit angular movement of the toggle link mechanism. This is clearly shown in Figure 3 the parts where shown

2

by chain dotted lines being in their loaded position from which position they can be moved with a minimum of effort through a dead centre position, the coiled compression spring 8 then coming into operation to move the toggle links into the full line position. The manner in which movement of the toggle link mechanism is brought about will be described more fully in a later part of the description.

Rigidly associated with component 5 and links 7 is a locking jaw 15 which co-operates with a peg 16 carried by a fixed part of the vehicle body, such as for example, a door pillar. The pawl 15 is shaped to engage and enclose the peg 16 over approximately half its circumference, the jaw including two spaced limbs 17 and 18, limb 18 being slightly longer than limb 17 for a purpose herein-after described. Assuming that the component parts of the toggle link mechanism have been moved into their loaded position as indicated by chain dotted lines in Figure 3, on the door being moved towards its closed position, limb 18 will engage the fixed peg 16, thereby causing the jaw and links 7 to pivot about the knife edge 3 over the dead centre position of the toggle link mechanism, the spring 8 then taking charge to move the jaw 15 and toggle link components into the full line position shown in Figure 3 thus effecting final closure movement of the door. It will be appreciated that limb 17 when moved into the full line position will effectively resist opening movement of the door, but to prevent any possibility of the door being opened except by operation of the handle, it is proposed to provide locking mechanism which is shown clearly in Figure 2 and takes the form of a plate 19 pivoted at 20 to carrier plate 1, plate 19 being provided with ratchet teeth 21 which co-operate with a pawl 22 pivoted to plate 1 at 23 and urged into its operative position by means of a helical tension spring 24. Plate 19 is formed with a slot 25 in which slides a pin-like projection 26 forming a continuation of bearing member 10 and knife edge 14, the pin projecting through an arcuate slot 27 formed in carrier plate 1.

As will be seen clearly from Figure 2 which shows the door latching device in its locked door closed position, pawl 22 has engaged one of the teeth 21 and pin 26 has entered the lower end of slot 25 out of which it cannot move without pivotal movement of plate 19 being permitted. Consequently the toggle link mechanism will be maintained in the full line position shown in Figure 3 with the locking jaw 15 in operative engagement with the pin 16, thereby maintaining the door securely in its closed position.

The door latching device includes an additional safety device in the form of a pivoted catch 28 which trails when engaging and co-operates with a striker plate 29 on a fixed part of the vehicle, the catch being urged into its operative projected position by means of a coil spring 30. A further fixed plate 31 is mounted on a fixed part of the vehicle under which a radius on the top of the jaw rides in the locked position, thus preventing movement of the door due to the camming action of the pin. This projection also provides vertical location for the door.

The mechanism provided for opening the door and loading the toggle link mechanism will now be described. Carrier plate 1 has associated with it bearing lugs 34, 35 and 36 in which a vertically positioned spindle 37 is mounted for limited angular movement. The spindle 37 has freely mounted on its upper end a channel shaped bracket 38 (Figs. 1 and 2), whilst a lug 39 on spindle 37 carries an upstanding pin 40 which passes through an arcuate shaped slot in the lower part 38a of the bracket, a coiled spring 41 encircling the upper end of spindle 37 and serving to return the outside door handle 42 to its

normal position shown in Figure 6. The outside door handle 42 is connected with bracket 38 by means of a single bolt 43 passing through a hole 43a in the bracket and consequently movement of the outside handle 42 in an opening sense will, when the extremity of the arcuate slot in bracket 38 engages pin 40, cause spindle 37 to be moved angularly about its longitudinal axis.

Spindle 37 carries at its lower end a cam face 44 which co-operates with projection 45 on the pawl 22 to move the pawl out of engagement with the ratchet teeth 21 as a result of angular movement of spindle 37, thereby disengaging the pawl from the ratchet teeth to permit of opening movement of the door under the action of either the outside handle 42 or the inside handle 46 (see Figure 5). The spindle 37 carries a lug 47 having a pin 48 which enters the slot 49 (Fig. 4) in a link 50, the latter being pivotally connected at 51 to the catch 28. It will be appreciated that the spring 30 will normally urge the catch 28 into its operative position, but on the latter striking the striker plate 29 on the vehicle body the catch will first be forced back, this being possible by the pin and slot connections 48 and 49, the catch then moving into its operative position under the action of its associated spring when the door is fully closed.

Pivotal movement of the locking jaw 15 to cam the latter out of engagement with fixed pin 16 is brought about by engagement of a lever 52, which is secured to spindle 37, with one of the links 7, the extremity of the lever 52 passing through a slot 53 in carrier plate 1 into engagement with the link. In this way the toggle link mechanism will be moved from the full line position through a dead centre position into the chain dotted line position shown in Figure 3 in which position the locking jaw can disengage itself from the pin 16 and allow the door to be fully opened. By virtue of the pin and slot connection between the outside door handle carrying bracket and pin 40, return movement of the handle will not bring about any return rotational movement of spindle 37 and consequently the toggle link mechanism and jaw 15 will remain in the chain dotted line position, that is to say, ready to assist closure of the door if the jaw 15 is re-engaged with the pin 16.

To open the door from the interior of the vehicle the usual inside handle 46 is provided which is connected by means of a system of links 54, 55 and double ended lever 56 with pin 40. In Figure 5 the door is indicated by reference numeral 57 and the fixed part of the vehicle by reference numeral 58.

Although the faces 12 and 13 co-operating with the faces of the knife edge 14 may be sufficient to limit angular movement of the toggle link mechanism, other means may be provided for this purpose. For example, a stop member 59 may be carried by one or other of the carrier plates 1 or 2, or the slot 60 formed in carrier plates 1 and 2 may be so dimensioned that it restricts that pivotal movement of that part of the locking jaw 15 indicated by reference numeral 61 which projects through carrier plate 1 via the slot 60.

It will be appreciated that by providing the plate 19 with a number of ratchet teeth provision is made for locking the door against opening movement even though the locking jaw 15 and pin 16 have not for any particular reason fully engaged. Such an arrangement is also useful in compensating for any faulty fitting of the device, or structural defects of the door which may have arisen during course of manufacture which tend to force the door open to an extent which might neutralize the closing action of the lock.

In the construction hereinbefore described arming of the toggle link mechanism is consequent upon movement of the outside or inside door handle and opening movement of the door in its initial stages. Such arming, however, may be effected not as a direct result of movement of the handle, but as a result of hinging opening move-

ment of the door. In such a case the toggle link mechanism may be arranged adjacent the door hinges and in this case movement of the toggle link mechanism over a dead centre position into its armed position may be brought about by means of a cam, links or other mechanism associated with the door, the toggle link mechanism being in this case connected with the locking jaw by means of a link or other remote connecting member.

It will be appreciated from the foregoing description that door slamming will be unnecessary, the toggle link mechanism taking charge to complete the closing movement once the limb 18 on the locking jaw has contacted the pin 16.

By the employment of knife edge bearings it is possible to employ a very heavily loaded toggle mechanism which at the same time can be moved through a dead centre position with a minimum of force. Furthermore, it will be appreciated that such knife edge bearings will be located in a relatively inaccessible position and by virtue of their construction will operate satisfactorily without the necessity for periodical lubrication.

I claim:

1. A door latch device intended particularly for use in connection with the doors of motor vehicles including a locking jaw for cooperating with a peg or its equivalent, either said jaw or peg being associated with the door and the other component associated with a fixed part such as the vehicle body, said device comprising a support, a pair of spaced pivots on said support, a spring urged toggle link mechanism mounted on and between said pivots, a locking jaw fixed with one link of said toggle link mechanism and swingable therewith, means on said support and engageable with said toggle link mechanism for locking said mechanism in its beyond center position in which the door is closed to retain the door closed, a handle, and means connecting said handle with said locking means and said toggle link mechanism and operative upon opening movement of said handle for unlocking said locking means and moving said toggle link mechanism through dead center to disengage said jaw and peg and open the door, whereby said spring urged toggle link is movable through a dead center position as a result of engagement of the jaw and peg during closing movement of the door for drawing the jaw and peg together into interlocking engagement and the door into its fully closed position, said handle being connected through the medium of a rotatable spindle journaled on said support and carrying a lever engageable with the toggle links to move the latter through a dead center position and the jaw out of locking engagement with the pin, said positive locking means including a pawl and ratchet mechanism, the pawl being moved out of engagement with the ratchet by a cam carried by said spindle upon initial movement of the handle in an opening sense, and said ratchet comprising a pivoted lever having a slot formed therein which co-operates with a pin on the toggle links, the pin and plate being maintained interlocked when the pawl is in engagement with any one of the ratchet teeth.

2. A device as claimed in claim 1 including a spring urged catch pivotally mounted on said support for co-operating with a striker plate and withdrawable by operation of the door handle through a crank on said spindle and a link having connections with said catch and said crank, one of said connections being a pin and slot connection.
